JOINT BRACE FOR REDUCING
SWELLINGS

Rosabelle Halyard, Brooklyn, N. Y.

Refiled for application Serial No. 520,224, January 29, 1944. This application October 10, 1945, Serial No. 621,455

1 Claim. (Cl. 128—156)

1

This invention relates to new and useful improvements in a joint brace for reducing swelling.

This is a refile of my original application filed January 29, 1944, Serial Number 520,224 now abandoned.

More specifically, the invention proposes the construction of a joint brace adapted to be engaged upon one's finger, wrist, ankle or similar joint to apply pressure thereto to reduce swelling and support the injured member in a rigid state to assist it to return to a normal condition, and to reduce pain.

Still further it is proposed to characterize the joint brace by a flexible band of rubber, cloth or similar material arranged in a manner to encircle the joint, and which is provided with a support strip adjustably mounted thereon for transmitting a firm supporting pressure to the joint or limb.

Another object of the invention proposes characterizing the support strip by a piece of flexible metallic material disposed between layers of the flexible band and provided with portions extended therefrom in a manner to be shifted relative to the flexible band to assume the most comfortable position about the injured joint or limb.

For further comprehension of the invention, and of the objects and advantages thereof, reference will be had to the following description and accompanying drawings, and to the appended claim in which the various novel features of the invention are more particularly set forth.

In the accompanying drawing forming a material part of this disclosure:

Fig. 1 is a view of a hand provided with a finger brace and a wrist brace, constructed in accordance with this invention.

Fig. 2 is a sectional view through the finger brace taken on the line 2—2 of Fig. 1.

Fig. 3 is a sectional view taken on the line 3—3 of Fig. 2.

Fig. 4 is a sectional view through the wrist brace taken on the line 4—4 of Fig. 1.

Fig. 5 is a perspective developed view of the wrist brace.

Fig. 6 is a sectional view taken on the line 6—6 of Fig. 5.

The joint brace for reducing swelling, according to this invention, is illustrated in the form of an article for use upon one's fingers or toes. It is characterized by a flexible band 10 which is constructed of layers of cloth material, but which may also be constructed of leather, rubber or other similar material. The edge portions of the layers 10 are secured together by means of stitches

2

11. The flexible band is adapted to be engaged over one's joint or limb and is provided with a tab portion 12 by which the band may be gripped for assisting its positioning upon the finger or limb.

10 A support strip 13 is adjustably mounted on the band 10 for transmitting a firm supporting pressure upon the joint or limb. This support strip is characterized by a strip of flexible metal material disposed between the layers 10. The flexible strip 13 has its ends 14 rolled and extended through an elongated slot 15 formed in the outermost layer 10. The extension of the rolled ends of the metallic strip 13 through the slot 15 permits the strip 13 to be adjusted relative to the flexible band to engage about the injured area at a most comfortable position and apply pressure thereto to reduce the swelling.

20 In Figs. 4—6 the joint brace is characterized by a device for encircling one's wrist, ankle or other similar area. It is characterized by a flexible band 20 formed of superimposed layers of material and provided at one end with tab portions 21 for assisting in engaging the band 20 in position. 25 The opposite end of the band 20 is provided with an elongated slot 22 through which the tabs are adapted to be projected, as shown in Figs. 1 and 4. After being projected through the slot 22 the tabs 21 are adapted to be engaged about the band 20 in opposite directions to be tied together on the side of the band opposed to the side formed with the slot 22, as clearly shown in Fig. 4.

30 A support strip 23 of metal material is disposed between the layers of the flexible band and has one end 24 rolled and projected through an elongated slot 25 formed in the topmost layer of the flexible band 20. The rolled end 24 of the support strip 23 permits the position of the support strip 23 to be adjusted relative to the flexible band 20 to assume a most comfortable position upon the injured area. The support strip 23 is formed with an open side 26 permitting the removal of the support strip 23 from its normal position between the layers of the flexible band 20, permitting the flexible band to be easily laundered.

40 While I have illustrated and described the preferred embodiments of my invention, it is to be understood that I do not limit myself to the precise constructions herein disclosed and the right 45 is reserved to all changes and modifications coming within the scope of the invention as defined in the appended claim.

Having thus described my invention, what I claim as new, and desire to secure by United States Letters Patent is:

A joint brace for reducing swelling, comprising a flexible band for encircling one's joint or limb and having a tab portion for assisting in engaging it in position, and a support strip adjustably mounted on said band for transmitting a firm supporting pressure upon said joint or limb, said flexible band being formed of superimposed layers having their edge portions stitched together, said support strip comprising a length of metallic material disposed between the layers of said band and having their ends rolled and extended from said band through a slot formed in one of said layers.

ROSABELLE HALYARD.
